UNITED STATES PATENT OFFICE

HARRY E. NORVIEL, OF ANDERSON, INDIANA, ASSIGNOR TO DELCO-REMY CORPORATION, OF ANDERSON, INDIANA, A CORPORATION OF DELAWARE

IGNITION SWITCH

Application filed April 13, 1929. Serial No. 354,761.

This invention relates to a standardized ignition coil and lock switch unit, and it is an object thereof to provide an efficient lock switch of the rotary type that may be easily actuated by the plunger type of lock.

It is a further object of the invention to provide a contact device of the class described, that is simple in design and capable of manufacture at a relatively low cost.

Further objects and advantages of the present invention will be apparent from the following description, reference being had to the accompanying drawings, wherein a preferred form of embodiment of the present invention is clearly shown.

In the drawings:

Fig. 1 is an elevational view with parts broken away to show in section certain parts of the instant invention, the section being substantially that represented by the section lines and arrows 1—1 of Figs. 2 and 3.

Fig. 2 is a sectional view substantially along the line 2—2 and in the direction of the arrows of Fig. 1.

Fig. 3 is a rear view in elevation of the lock barrel assembly and contact device, substantially as would appear along the line and in the direction of the arrows 3—3 of Fig. 1.

Fig. 4 is a fragmentary view of the contact device and actuator assembly, certain parts thereof being broken away and shown in section for clearness of illustration.

Fig. 5 is an exploded view of the contact actuator device contributing to the instant invention.

With particular reference to the drawings, 20 represents a case or can enclosing the usual ignition coil, and the can has inter-fitting relation with the sleeve 21 projected beyond the coil unit to provide a switch housing which is closed by a frame 23 of a lock barrel assembly. The other end of the case 20 is provided with a coil cap 24 which, among other appointments, supports the terminal posts 25, 26 and 27. These posts are connected to and through the coil within the case 20 by means of conductors 28, 29 and 30, with switch terminals 31, 32 and 33 moldably secured within the body of a coil base 34. The base 34 is retained within the can 20 by means of the

peripheral flange 35 against which it seats. The coil base 34 provides the back wall of a switch enclosure and is centrally recessed to form an annular depression 36 for a purpose later to be described.

The frame member 23 as earlier stated completes the switch housing or a closure for the member 21 and is centrally provided with a longitudinal bore which reciprocably receives a lock barrel 40. The lock barrel 40 carries a key cylinder 41 manipulatable by a key 42 and adapted to withdraw the bolt 43 from a recess 44 in the side wall of the tubular extension 45 supporting the lock barrel 40. The extension 45 carries a set screw 46 engaging a guide slot 47 in the barrel operating as a stop for longitudinal movement of the barrel 40 within the frame 23. A second aperture 48 in the tubular extension 45 provides for reception of the bolt 43 when the barrel 40 is moved to the projected position in which the switch is in a circuit closed relation, thereby allowing removal of the key 42 from the lock cylinder 41.

The inner end of the lock barrel 40 is provided with three aligned apertures 50, 51 and 52 for receiving and securing thereto a driving cup 53. The driving cup 53 is of cylindrical formation, the side walls of which are provided with the spiral slots 54 and 55. The bottom 56 of this cup is centrally apertured at 57 to receive a screw 58 driven therethrough and into the threaded aperture 51 of the lock barrel 40. Tangs 59 and 60 are struck from the bottom of the cup 53 substantially as illustrated in Figs. 1 and 5 so as to cooperate with the apertures 50 and 52 for securing the cup 53 in driving relation with the lock barrel 40. It will be noted that the slots 54 and 55 run from the cylindrical portion of the cup 53 over the edge thereof and slightly into the bottom 56 thereof, for a purpose that will presently appear.

A second cup 61 of larger diameter and centrally apertured at 62 is provided with the radial tangs 63 and 64 designed to have an inter-fitting engagement with the slots 54 and 55 of the driving cup 53, the aperture 62 being sufficiently large to receive the cup 53 therein. The cylindrical wall of the cup

100

61 is provided with peripheral tangs 65, 66 and 67 for support and retention of the remainder of the contact device as will presently appear.

- 5 The movable contact and support for this device comprises the substantially triangular plate or ring 70, each apex of which is deformed with the spherical embossments 71, 72 and 73 to provide contact points adapted for 10 engagement with the switch terminals 31, 32 and 33 respectively. The inner edge of the ring 70 is provided with the tangs 74, 75 and 76 which cooperate with notches 78, 79 and 80 of an insulating plate 81 and notches 82, 83 15 and 84 of an insulating plate 85 for securing the contact element 70 thereto. The insulating plates 81 and 85 are of ring formation as exhibited in Fig. 5 and are centrally apertured with deformations at the inner periphery thereof which provide the notches just 20 described. The outer periphery of the insulating plate or ring 81 is notched at 86, 87 and 88 while the plate 85 is similarly notched at 89, 90 and 91. It will be noted from the 25 illustration that the plates 81 and 85 are substantially alike in formation except that the notches 86, 87 and 88 of the plate 81 project further into the body of the plate than do the similar notches 89, 90 and 91 of the plate 85, 30 as shown in Figs. 1 and 5.

In assembling the structure the contact plate 70 and the insulation plates 81 and 85 are secured together, being superimposed upon one another in the order of their mention, and so that the tangs 74, 75 and 76 of the contact plate 70 are received within the notches 78, 79 and 80 of the plate 81 and the notches 82, 83 and 84 of the plate 85, and the said tongues are then bent over against the 40 body of the ring 85 as shown in Fig. 1. A contact urging spring 95 is then inserted within the cup 61 and the contact plate and insulating support sub-assembly are then placed upon the spring 95 which is then compressed 45 so that the plates 81 and 85 with their notches 86, 87 and 88, and 89, 90 and 91 respectively will be disposed opposite of the tangs 65, 66 and 67 of the cup 61.

While the elements are held in this position 50 the ends of the tangs 65, 66 and 67 are bent inwardly substantially at right angles so as to lie wholly within the notches 86, 87 and 88 respectively of the plate 81, as shown in Fig. 1. By this construction, the contact 55 plate 70 is resiliently mounted upon the cup 61 and provides a maximum amount of movement to and from the cup member 61 in the minimum amount of space, since no space for clearance need be made between the contact 60 member 70 and the bent over tangs of the cup 61. The cup 53 is then passed bottom end first through the aperture 62 of the cup member 61 with the slots 54 and 55 passing over the tangs 63 and 64, and after the tangs 65 65 59 and 60 of the cup 53 have been inserted in

the apertures 50 and 52, the retaining screw 58 is passed through the aperture 57 and driven into the threaded recess 51 of the lock barrel 40. The contact device and the actuator assembly is now in assembled form and when fixed within frame 23 is placed within the housing 22 so that the cup member 53 is aligned with the annular recess 36 of the coil base 34, a compression spring 96 being placed within the cup 53 disposed against the bottom thereof and seated within the annular recess 36 for urging the lock barrel 40 to the projected or circuit closed relation.

In the completed assembly the frame 23 telescopically engages the sleeve 21 and is retained in engagement therewith by the bent over tangs 97 seated within the peripheral notches 98, 99, 100 and 101 of the frame member 23, as illustrated in Figs. 3 and 4. The contact ring 70 and its insulating support will then be maintained in floating engagement with the switch contacts 31, 32 and 33, the resilient connection between the cup 61 and the plates 81 and 85 providing for a firm, yet yielding, engagement therebetween, due to the contact urging spring 95, yet restraining separation of the switch assembly by reason of the tangs 65, 66 and 67 seating within recesses of the plates 81 and 85.

From the foregoing description, it will be 95 obvious that the key 42 when inserted within the key cylinder 41 permits withdrawal of the bolt 43 from the recess 44 which allows the spring 96 to project the lock cylinder 40 to the extended or circuit closed position, and with it the driving cup 53. Due to the guiding function of the pin 46 and slot 47 the lock barrel 40 is restrained from turning within the tubular extension 45, and due to the non-rotatable engagement between the driving cup 53 and the lock barrel 40 through the tangs 59 and 60 seated within the apertures 50 and 52 of the lock barrel 40, the driving cup 53 is capable only of a longitudinal or reciprocable movement within the key frame 100 23. However, the interfitting driving engagement between the driving cup 53 and the contact supporting cup 61, that is, the spiral slots of the cup 53 within which are positioned the radial tangs of the cup 61, will 105 translate the reciprocable movement of the cup 53 to rotary movement of the cup 61, which, due to the driving engagement with the movable contact plate 70, will rotate that plate into and out of engagement with the switch contacts 30, 31 and 32 supported by the coil base 34. Therefore, reciprocable movement of the cup 53 will produce relative rotary movement of the cup 61.

The cup 53 in addition to supplying part 125 of the inter-engaging driving connection between the key cylinder 40 and the movable contact plate provides a housing for the plunger return spring 96, and also provides a journal like bearing for the contact sup- 130

- porting cup 61. It will be noted that another bearing surface for the cup 61 is provided by the rear end of the tubular extension 45 supporting the lock barrel 40, and this bearing also provides in a way an abutment against which the contact urging spring 95 may seat itself in order to resiliently support the contact plate 70 against the coil base 34 and the contact elements 30, 31 and 32.
- 10 Thus I have provided a novel switch actuating mechanism, which efficiently translates the longitudinal movement of the lock barrel actuator to rotary movement of the contact plate whereby the contact points are always kept clean of oxidized material through the rubbing action that takes place between the contacts as they are moved into and out of circuit closing relation.
- While the form of embodiment of the present invention as herein disclosed, constitutes a preferred form, it is to be understood that other forms might be adopted, all coming within the scope of the claims which follow.
- What is claimed is as follows:
- 25 1. A standardized ignition coil and lock switch unit comprising a rotatable switch contact, means resiliently supporting said contact, a reciprocable lock plunger and cooperating cup means connecting said lock plunger for movement of said contact member.
2. A standardized ignition coil and lock switch unit comprising a rotatable switch contact, means resiliently supporting said contact, a reciprocable lock plunger and motion translating means connecting said lock plunger with said contact member, said connecting means comprising, a pair of inter-fitting cups, one of said cups resiliently supporting said contact.
3. A standardized ignition coil and lock switch unit comprising a rotatable switch contact, means resiliently supporting said contact, a reciprocable lock plunger and motion translating means connecting said lock plunger with said contact member, said connecting means comprising, a driving cup secured to said lock plunger, a contact actuating cup drivingly connected to said driving cup and means providing longitudinal and rotative movement between the said cups.
4. A standardized ignition coil and lock switch unit comprising a rotatable switch contact, means resiliently supporting said contact, a reciprocable lock plunger and motion translating means connecting said lock plunger with said contact member, said connecting means comprising, a driving cup secured to said lock plunger, a contact actuating cup drivingly connected to said driving cup and means providing longitudinal and rotative movement between the said cups, one of said cups supporting means for moving one of the cups relative to the other.
5. A standardized lock switch coil unit comprising a member providing switch terminals, a case forming a housing about said terminals, a lock barrel assembly closing said housing and drivingly supporting a switch mechanism, said switch mechanism comprising a contact member engageable with said terminal members, a pair of inter-engaging cup members resiliently supporting said contact member and drivingly connecting the same with said lock barrel assembly.
6. A standardized lock switch unit comprising a member supporting switch terminals, a case enclosing said terminals, a lock barrel assembly drivingly supporting a switch mechanism, said switch mechanism comprising, a pair of interengaging cup members, one of said cup members resiliently supporting a contact member for engagement with each terminal member and capable of rotary movement therewith, and means common to said cup members for producing relative rotary movement therebetween upon longitudinal movement of one of said cup members, said lock barrel assembly connected to and adapted for longitudinal movement of one of said cup members.
7. A standardized lock switch comprising a member supporting switch terminals, a case forming a housing about said terminals, a lock barrel assembly closing said housing and drivingly supporting a switch mechanism, said mechanism comprising, a driving cup fixed to said lock assembly for reciprocation therewith, a second cup having inter-fitting provisions with said first cup and resiliently supporting a contact member, said inter-fitting provisions producing relative rotary movement of the second cup member upon reciprocable movement of said first cup member.
8. A standardized lock switch comprising a member supporting switch terminals, a case enclosing said terminals, a lock barrel drivingly supporting a switch mechanism, said switch mechanism comprising, a contact member in floating engagement with said terminal members, a supporting cup insulatingly and resiliently supporting said contact member, a driving cup secured to said lock barrel assembly, inter-fitting provisions between said cup members so that reciprocable movement of one of said cup members will be translated to rotary movement of the other of said cup members.
9. A standardized lock switch coil unit comprising, switch terminals, a case enclosing said terminals, a lock barrel assembly driving a switch mechanism, said switch mechanism comprising, a driving cup capable of longitudinal movement with said lock barrel, a contact supporting cup disposed about the first cup, and resiliently supporting a contact member for engagement with said terminal members, driving provision

connecting said cups so as to translate reciprocable movement of the first cup to rotary movement of the second cup.

10. A standardized lock switch coil unit comprising a member supporting said coil and providing switch terminals, a case forming a housing about said terminals, a lock barrel assembly closing said housing and drivingly supporting a switch mechanism, said switch mechanism comprising, a pair of inter-fitting cups, one of said cup members resiliently supporting a contact member for coincidental engagement with each of said switch terminals, the other of said cup members having provisions for driving said first cup member.

11. The combination set forth in claim 10 in which the inter-fitting relation between the cups includes one or more spiral slots in the driving cup which receive radial tangs of the second cup whereby one of said cup members will be rotated upon reciprocation of the other cup member.

12. In a lock switch coil unit the combination comprising, a coil base providing switch terminals and forming the back wall of the switch housing, a movable contact device for cooperation with the switch terminals comprising a contact plate secured to a pair of nonconducting rings, a supporting cup secured to the rings and thereby insulatingly supporting the contact plate, said cup member being centrally apertured and provided with radial tangs, a second cup providing spiral grooves for inter-fitting relation with said tangs, said second cup supported by the lock barrel assembly providing a closure for said switch housing, the inter-fitting relation between said cup members providing rotary movement of the first cup upon reciprocation of the second cup member.

13. In a lock switch coil unit the combination comprising, a coil base providing switch terminals and forming the back wall of the switch housing, a movable contact device for cooperation with the switch terminals comprising a contact plate secured to a pair of nonconducting rings, a supporting cup secured to the rings and thereby insulatingly supporting the contact plate, said cup member being centrally apertured and provided with radial tangs, a second cup disposed within the aperture of the first cup and drivingly engaging the tangs thereof, means supporting the second cup and adapted for reciprocation thereof, said driving engagement between the cups translating reciprocal movement of the driving cup to rotary movement of the first cup.

14. In a lock switch coil unit the combination comprising, a coil base providing switch terminals and forming the back wall of the switch housing, a movable contact device for cooperation with the switch terminals comprising a contact plate secured to a pair of

nonconducting rings, a supporting cup secured to the rings and thereby insulatingly supporting the contact plate, means within the cup resiliently supporting the rings, said cup member being centrally apertured and provided with radial tangs, a second cup having spiral grooves in the wall thereof, said cup members providing an inter-engaging relation therebetween whereby the tangs of the first cup are positioned within the grooves of the second cup, and the said second cup is adapted for longitudinal movement within the aperture of the first cup, and means providing for longitudinal movement of the second cup whereby the first cup will be rotated relative thereto.

15. A standardized lock switch coil unit comprising a member providing switch terminals, a case enclosing said terminals, a lock assembly drivingly supporting a switch mechanism, said switch mechanism comprising, a pair of inter-engaging cup members, one of said cup members resiliently supporting a contact member for engagement with each terminal member and capable of rotary movement therewith, said inter-engaging cup members translating reciprocal movement of one to relative rotary movement of the other.

16. A standardized lock switch coil unit comprising a member providing switch terminals, a case forming a housing about said terminals, a lock barrel assembly closing said housing and driving a switch mechanism, said switch mechanism comprising, a pair of inter-engaging cup members, one of said cup members resiliently supporting a contact member for engagement with each terminal member and capable of rotary movement therewith, said inter-engaging cup members translating movement of the lock barrel to said switch mechanism, said lock barrel adapted for reciprocably moving one of said cup members.

In testimony whereof I hereto affix my signature.

HARRY E. NORVIEL.
